UNITED STATES PATENT OFFICE.

THORLEIPUS P. THORLEIPSON, OF STONY HILL, MANITOBA, CANADA.

BOMBING DEVICE.

1,364,009.

Specification of Letters Patent. Patented Dec. 28, 1920.

Application filed December 15, 1919. Serial No. 345,093.

To all whom it may concern:

Be it known that I, THORLEIPUS P. THORLEIPSON, a subject of the King of Great Britain, residing at Stony Hill, in the Province of Manitoba, and Dominion of Canada, have invented new and useful Improvements in Bombing Devices, of which the following is a specification.

This invention relates to a bombing attachment for rifles and the principal object of the invention is to provide means whereby a plurality of bombs may be shot from the rifle in rapid succession.

Another object of the invention is to provide means for feeding the bombs into firing position by the movement of the breech bolt.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of a rifle supplied with my invention.

Fig. 2 is a sectional view of the forward end of the device.

Fig. 3 is a like view with loading means in contracted position and with a bomb in firing position.

Fig. 4 is a perspective view of the carrier.

Fig. 5 is a sectional view of the reel.

In these views 1 indicates the gun or rifle which may be of any desired type and which is adapted to be supported in firing position by the tripod 2. In carrying out my invention I locate a sleeve 3 on the barrel of the gun and this sleeve is slidably connected with the barrel by means of the slot 4 and the pin 5. I also place a guiding member

6 on the end of the barrel and this member is held on the barrel in any desired manner. As shown, it is held to the barrel by the sight 7 of the gun engaging a bayonet slot in the member. The outer end of this member overlaps the end of the barrel and the under part of this overlapping portion is provided with a recess 8 for guiding the stems of the bombs to the bore of the barrel.

55 A spring 9 is placed on the barrel and has one end abutting the sleeve 3 and its other

end abutting the guide 10 which is placed on the barrel. This spring tends to hold the sleeve against the inner end of the guiding member 6.

60

The bomb carrier 11 consists of the loop-like frame 12 which is formed with the parallel vertical portions 13, provided with the eyes 14 midway their ends which are engaged by the pivot pins 15 on the sleeve 65 3. In this way the carrier is pivotally supported by the sleeve. A semi-circular arm 16 has its ends connected with the ends of the frame 12 and this arm carries a plurality of guiding sleeves 17. The ends of 70 the frame 12 also have connected therewith the arms 18 and these arms support the semi-circular frame 19. This frame is provided with a plurality of cone-shaped sockets 20 for receiving the bombs 21. These 75 bombs are provided with the stems 22 which extend through the holes 23 at the inner ends of the sockets and through the guide sleeves 17.

A reel 24 is mounted in a case 25 carried 80 by the frame 19 and this reel is provided with a winding spring 26 and ratchet mechanism 27. A cable 28 has one end connected with this reel and this cable passes over the pulley 29 through the guide 10 and has its 85 other end connected to the breech bolt 30 as at 31. A cable has one end connected to the other rear end of the breech bolt and this cable passes through a guide 33, located adjacent the end of the stock and then passes 90 forwardly through a guide 34 and has its other end connected with the sleeve 3. The spring reel is arranged to take up the slack 95 in cable 28 caused by forward movement of the breech bolt and the ratchet mechanism will prevent this slack from being unwound from the reel when the bolt moves rearwardly. In this way the cable is shortened every time the breech bolt is operated and thus the bomb carrier is swung upwardly on 100 its pivots.

In the operation of the device the cable is unwound from the reel, by manipulating the ratchet so that the bomb carrier is in its lowest position. Then the breech bolt is 105 opened to load the gun and in this opening movement the cable 28 is caused to raise the bomb carrier to bring the first bomb into the recess 8 of the guiding member. As before stated, this recess will guide the 110 stem of the bomb to a position in alignment with the end of the bore of the barrel.

Then when the breech is closed the cable 32 is caused to pull back the sleeve 3 against the tension of the spring and as the carrier is connected with said sleeve said carrier 5 will move relative to the gun and thus the end of the stem of the bomb will be caused to enter the bore of the barrel, as shown in Fig. 3. The slack in cable 28, caused by this forward movement of the breech bolt, 10 will be taken up by one spring reel. When the cartridge is fired the bomb will be thrown from the gun in the usual manner. The breech bolt is then manipulated to eject the old cartridge and place a new one in 15 the firing chamber and this action will raise a new bomb into firing position and so on until the bombs are all discharged. After each movement of the breech bolt the cable 32 is shortened so that the bomb carrier is 20 raised step by step.

The bombs may be held in the carrier by any suitable means to prevent them from falling out of the carrier. Such means, however, must be easily broken so as to not 25 interfere with the discharging of the bombs.

It is thought from the foregoing description that the advantages and novel features of my invention will be readily apparent.

I desire it to be understood that I may 30 make changes in the construction and in the combination and arrangement of the several parts, provided that such changes fall within the scope of the appended claims.

What I claim is:—

1. In combination with a gun, a bomb 35 carrier for supporting a plurality of bombs, a sleeve slidably mounted on the barrel of the gun, means for pivotally connecting the carrier to said sleeve and means connecting the firing mechanism of the gun with said 40 sleeve and carrier for successively bringing the bombs to the muzzle of the gun.

2. In combination with a gun, a bomb carrier, a sleeve slidably mounted on the gun, means for pivotally connecting said 45 carrier to the sleeve, a guiding member on the end of the barrel having a recess therein for guiding the bombs to the bore and cables connecting the sleeve and carrier to the breech bolt for bringing the bombs into 50 firing position by the movement of said bolt.

3. In combination with a gun, a sleeve slidably mounted thereon, a spring engaging said sleeve, a bomb carrier pivotally connected with said sleeve, a spring reel on said 55 frame, ratchet mechanism for preventing the unwinding of said reel, a cable having one end connected with said reel and its other end connected with the breech bolt, a second cable connecting the breech bolt 60 with the sleeve and guiding means connected with the gun for guiding the bombs into firing position.

In testimony whereof I affix my signature.

THORLEIPUS P. THORLEIPSON.
